UNITED STATES PATENT OFFICE.

WELLES ROKOSKI, OF CARLOS, MINNESOTA.

WALL CONSTRUCTION.

Application filed August 14, 1925. Serial No. 50,243.

My invention relates to improved construction of plastered walls and the object is to make a wall having plastering reinforced by materials that will retain the heat 5 in the building and also prevent cracking of the plaster and incidentally such non-cracking plaster will promote cleanliness by eliminating cracks for vermin to gather in.

The main idea of the invention is to 10 sure in or on the wall some flexible material such as straw or hay and then apply the plaster in such a manner that its rear side gets partly inter-mixed with and stuck to the flexible material and then face off the 15 plaster in any suitable manner. The new means and method may also be applied for outside plastering or so-called stucco work.

In the accompanying drawing:

Fig. 1 is an inside elevation of a partly 20 completed portion of a frame house wall embodying my invention, in one of its forms.

Fig. 2 is a top view of Fig. 1.

Fig. 3 is an inside elevation of a wall portion embodying my invention in a certain 25 modified form.

Fig. 4 is a top view of Fig. 3.

Fig. 5 is an inside elevation of a wall with another modification.

Fig. 6 is a top view of Fig. 5.

Fig. 7 is an elevation of a portion of a 30 wall with my invention further modified.

Fig. 8 is a top view of Fig. 7.

Fig. 9 is a detail view of a portion of a straw or hay cable used in forms of the 35 invention, similar to that shown in Figs. 1 and 2.

Referring to the drawing by reference numerals, 10 designates the base portion of a wall having upright studdings 11 with 40 sheathing 12 and siding 13 (shown in Fig. 8). In some houses metal lath and stucco may finish the outer side of the wall.

The straw or other flexible material I employ may be applied in various ways. Thus 45 in Figs. 1 and 2 is shown that suitable horizontal wires 14 may be secured by staples 15 to the adjacent sides of the studdings 11, about midway between the outer and inner edges of each studding and the straw 16 wound about said wires preferably after being 50 twisted into cable or rope form as indicated in Fig. 9. In this case the stucco 17 is secured to the outer side of the wall by

sticking to and mixing with the straw, and the inside plaster 18 is likewise secured upon 55 the inner side of the wall and its surface finished in any desired manner.

In Figs. 3 and 4 ordinary lath 19 are spaced suitably apart and secured to the studdings by nails 20, and the straw is inserted as 16^a in vertical position alternately 60 inside and outside the lath and then the plaster 18 applied.

Another modification is shown in Figs. 5 and 6, where a wire netting 21 is secured 65 by staples 22 to the inner edges of the studdings and a similar netting 21^a in Fig. 6 may be likewise secured to the outer edges of the studdings and the hay, straw or like 70 material 16^b may be filled in between the outer and inner netting between the studdings as shown in Fig. 6.

In the modification shown in Figs. 7 and 8, a strong wire 23 is secured in zig-zag formation down the inner sides of the studdings 75 and secured to them by either staples or nails 24. The straw 16^c is then spread upon or against said wires and held in place by a light wire netting 25 secured by staples 26 and the plaster 18 is then applied and finished. 80

The various modifications shown do not exhaust all the forms obviously involved in the method illustrated, nor are hay and straw, rags and waste, thread or yarn the 85 only materials that may be used to toughen the plaster and make the wall resist the escape of heat, but what is shown and described disclose the principle of the invention. 90

What I claim is:

1. The combination with a house wall of plaster put thereon and a soft grass-like material secured in the wall and partly intermixed with the rear side of the plaster, said soft material being twisted in the form of cables and as such projecting laterally outward into the plaster said wall having rigid bars and said cables being wound spirally about said bars. 95

2. The structure specified in claim 1 in which the wall has vertical studdings holding the rigid bars in horizontal position. 100

In testimony whereof I affix my signature.

WELLES ROKOSKI.
